UNITED STATES PATENT OFFICE.

ALEXANDER McD. HESS, OF BROOKLYN, NEW YORK.

SEWING MACHINE.

Application filed April 28, 1924. Serial No. 709,330.

To all whom it may concern:

Be it known that I, ALEXANDER McD. HESS, a citizen of the United States of America, residing at Brooklyn, county of Kings, and State of New York, have invented new and useful Improvements in Sewing Machines, of which the following is a specification.

This invention relates to machines for stitching fabrics or other materials and commonly referred to as sewing machines.

The main object of the invention is to so mount the needle and its connections that it may be caused to deviate from the usual straight row of stitching according to conditions external to the machine such as projections from the surface of the fabric or other guiding means.

A further object of the invention is to provide means whereby the needle is caused to so deviate from this usual straight line stitching as to correspond with exterior conditions such as projections upon the work or other defining means.

The invention will be found of great usefulness in connection with the securing hooks of hook and eye combinations to garments and the like. In stitching a covering to the hook tape, in securing this tape to the garment or in securing the hooks to the garment without the tape, the hooks are usually secured at their eyelets and are caused to lie flat upon the goods and are more firmly secured thereto if a line of stitching passes through the hooks and close to the bights of the hooks. With the usual machine, however, such stitching cannot be performed because the sewing mechanism cannot pass over the hooks. The present invention provides a solution of this difficulty in that the desired line of stitching may be made, the needle passing around the hooks as it reaches them.

Other and ancillary objects of the invention will appear hereinafter.

In the accompanying drawings which illustrate the invention—

Fig. 1 is a side elevation, partly broken away and partly in section, of the head of a sewing machine embodying the invention;

Fig. 2 is a section on the line 2—2 of Fig. 1 showing the needle in one position;

Fig. 3 is a section on the line 3—3 of Fig. 1;

Fig. 4 is a side elevation from the right

hand side of Fig. 1 of the lower portion of the apparatus shown therein;

Fig. 5 is a section, on an enlarged scale, partly broken away on the line 5—5 of Figs. 1 and 6;

Fig. 6 is a top plan view of the apparatus of Fig. 5, the same being a section on the line 6—6 of Fig. 1, the needle being shown in the position for the usual straight stitching; and

Fig. 7 is a view the same as shown in Fig. 6 but showing the needle in diverted position for avoiding the hook.

Referring to the drawings, the apparatus comprises the usual arm or frame 1 of a sewing machine in which is rotatably mounted a drive shaft to which is fixed the wheel 2. Mounted upon the arm is a post 3. Journaled upon the post 3 is an arm 4 in the outer end of which reciprocates the needle bar 5, the needle 6 being fixed in its lower end in the usual fashion and being thus driven toward and away from the work. Secured to the end of the arm 4 is a link 7 connected by a spring 8 with the frame or arm of the machine by a screw 9. The sewing thread 10 after passing through the usual guiding and tensioning devices passes through the eye of the needle 6 in the usual manner. The spring 8 is so arranged that it tends to hold the arm 4 in the position as shown in Fig. 2 but may be moved against the tension of the spring to cause the needle bar to move laterally, the head or frame being provided with slots 11 and 12 to permit this movement of the needle bar.

A presser foot 13 secured to the frame or arm 1 is provided and may be of usual construction except that it has a transversely extending arc-shaped slot 14 to permit lateral movement of the needle and also a longitudinal extending recess 15 which permits the hook 16 to pass beneath the presser foot as the goods or work is advanced in the sewing operation.

Also the machine has the usual table 17 upon which the work rests and in which is mounted the usual work advancing dog 18, it being understood that the apparatus is provided with the usual shuttle and other well known devices necessary to complete the stitching operation.

The needle bar is driven by means of a clamp 19 fastened upon it and connected by a ball and socket connection 20 with a driv-

ing rod 21 carrying a ball 22 at its other end which is fitted within a socket mounted upon one side of the driving wheel 2.

- 5 Fixed to the arm or frame 1 is a depending bracket 23 in the lower end of which is journaled a shaft 24 which has fixed to one end, the arm 25 extending at its upper end in proximity to the needle bar, and to the other end of the shaft 24 is fixed an arm 26 10 operatively related to an arm 27 by a pin and slot connection 28. The lower end of the arm 27 is secured to a lever arm 29 which is bifurcated into the two branches 30 and 31 which are pivoted at 32 and 33 15 in the bracket 34 fixed to the top of the presser foot. It is to be observed that the branch 30 is at the edge of the presser foot whereas the branch 31 is over the needle slot in the presser foot.
- 20 Secured to the branch 30 and extending into the needle slot in the presser foot and alongside the needle, is a cam plate 35 adapted to engage a hook 16 or other projection upon the goods.
- 25 It will now be apparent that, the needle being in the position with relation to the presser foot as shown in Figs. 1 and 6, the row of stitching 36 will be straight until the lower face of the cam 35 comes against the hook 16. The further progress of the fabric being sewed, or work, with the hook upon it will cause the cam to ride upon the hook pressing the arm 29 upwardly, the bifurcated portions 30 and 31 turning about the pivots 32 and 33. The outer end of the arm 29 thus rising, the arm 27 will be pushed upwardly thereby pushing the arm 26 upwardly and turning the shaft 24. This 30 will turn the arm 25 throwing its upper end 40 against the needle bar and pushing it laterally into the position as shown in Fig. 7 where, it will be seen, it is thrown to one side of the hook and upon further advance of the goods or work passes around the hook, the cam 35 after it has passed the hook dropping back to its normal position and permitting the needle bar to return to a position to stitch in the straight line of the row under the action of the spring 8, 45 and this can take place as often as a hook or other projection upon the work is encountered. It will be apparent also that the needle bar being free to move laterally but being held resiliently in normal position, it may be moved laterally in response to pushes of the hand of the operator as 50 may be required or in response to the outline of various patterns or in other ways and for various other sewing operations as well as that in relation to the securing of hooks. It will also be seen that the needle may be maintained in its displaced position, and place the stitching accordingly, by lengthening the operating face of the cam 35 to 55 the desired extent and also the row of stitch-

ing may be made to have any desired course by varying the depth of the cam surface at different points so that the needle is moved laterally back and forth accordingly.

As is well known in connection with the usual sewing machines the work advancing dog 18 is thrown upwardly and forwardly so as to engage the work and advance it under the needle while the last is in raised position and disengaged from the work, the dog then receding downwardly so as to disengage the work and leave it stationary under the needle and at the same time the dog moves backwardly to be in a position to again move upwardly and forwardly to again advance the work. The apparatus as is well known, is so related and organized that the work is advanced while the needle is in raised position so as to be clear of the work. This being the interval that the work is moved, it will be during this interval that the hook is forced beneath the cam so that the lateral movement of the needle bar in response to the rising of the cam 35 will take place when the needle is clear of the goods so that it is free to make such movement.

Also the rising of the dog to engage the goods may be taken advantage of for another purpose. In order that the cam 35 may rise quickly on encountering a hook, its inclined face may be made quite steep so that it may require considerable force to force the cam upwardly by its engagement with the hoop. To aid in raising the cam a foot 37 is fixed to the arm 30 of the bifurcation and passing down alongside the presser foot engages with the work 38 traveling in close relationship thereto, directly over the dog 18 so that as the dog rises as before referred to it will raise the foot 37, the arm 30, the arm 31 and the cam 35 connected thereto so that to accomplish the remainder of the movement the inclined face of the cam need not be made so steep and the certainty and ease of operation of the shifting of the needle is more readily accomplished.

While the invention has been illustrated in what is considered its best application it may have other embodiments without departing from its spirit and is not therefore limited to the structure shown in the drawings.

What I claim is:

1. In a sewing machine, the combination with a needle bar reciprocating toward and away from the work, of means mounting said bar to move laterally of its path of said reciprocation, said bar being adapted to be moved laterally and means cooperating with the work for moving the said bar laterally.
2. In a sewing machine, the combination with a needle bar, reciprocating toward and away from the work, of means mounting said bar to move laterally of its path of said

reciprocation, and means cooperating with projections on the work for moving the said bar laterally.

3. In a sewing machine, the combination 5 with a needle bar reciprocating toward and away from the work, of means mounting said bar to move laterally of the path of said reciprocation, a spring holding said bar in one lateral position and means cooperating 10 with projections on the work for moving said bar laterally against the force of said spring.

4. In a sewing machine the combination 15 with a needle bar reciprocating to drive the needle toward and away from the work, of means for mounting said bar to move laterally with relation to said reciprocating path, a cam passing in proximity to the work and adapted to be moved by projections thereon and operative means between said cam and said needle bar adapted to cause said bar to move laterally of said reciprocating path in response to movement of 20 said cam caused by engagement with said 25 projections.

5. In a sewing machine the combination 30 with a needle bar reciprocating to drive the needle toward and away from the work, of means for mounting said bar to move laterally with relation to said reciprocating path, a cam passing in proximity to the work and adapted to be moved by projections thereon and operative means between said cam and said needle bar adapted to cause said bar to 35 move laterally of said reciprocating path in response to movement of said cam caused by

engagement with said projections, and a spring biasing said needle bar in a direction lateral to said reciprocating path.

6. In a sewing machine the combination 40 with a needle bar reciprocating in a path to drive the needle to and from the work, arms pivoted to the head of said machine in which said bar reciprocates, said arms being adapted to turn on said pivots laterally 45 of said reciprocating path, a spring tending to hold said bar in one position laterally of said path, a presser foot, a cam movably mounted on said presser foot, and means operatively connected with said cam and operatively related to said bar whereby raising of said cam forces said bar laterally of said path.

7. In a sewing machine the combination 55 with a needle bar reciprocating in a path to drive the needle to and from the work, arms pivoted to the head of said machine in which said bar reciprocates, said arms being adapted to turn on said pivots laterally of said reciprocating path, a spring tending to hold 60 said bar in one position laterally of said path, a presser foot, a cam movably mounted on said presser foot, and means operatively connected with said cam and operatively related to said bar whereby raising of 65 said cam forces said bar laterally of said path, a work advancing dog and means cooperating with said dog adapted to assist the operation of said cam in shifting said bar.

In testimony whereof I have signed this 70 specification this 25th day of April, 1924.

ALEXANDER McD. HESS.
